CHARLES W. ANTILL AND WILLIAM L. SCHMOLLE, OF SAN FRANCISCO, CALIFORNIA;
SAID SCHMOLLE ASSIGNOR TO ANTILL PATENT WINDOW COMPANY, OF SAN FRANCISCO, CALIFORNIA, A CORPORATION OF CALIFORNIA.

LOCK FOR SLIDING WINDOWS.

1,116,531.

Specification of Letters Patent.

Patented Nov. 10, 1914.

Application filed November 30, 1912, Serial No. 734,279. Renewed March 30, 1914. Serial No. 828,160.

To all whom it may concern:

Be it known that we, CHARLES W. ANTILL and WILLIAM L. SCHMOLLE, subjects of the King of Great Britain, residing at San Francisco, in the county of San Francisco and State of California, have invented new and useful Improvements in Locks for Sliding Windows, of which the following is a specification.

10 The object of the present invention is to provide a window lock adapted for use in windows having horizontally sliding sashes, by which lock such sashes can be secured in any one of several positions and which will 15 be neat and inconspicuous in appearance and convenient in use.

In the accompanying drawing, Figure 1 is a front elevation of the lower portion of a window equipped with our invention, the 20 lower portion of one sash being broken away to show the locking device; Fig. 2 is a horizontal section of the window in its open position; Fig. 3 is an enlarged vertical section through a pivot of the 25 window sash; Fig. 4 is an enlarged broken plan view of a slideway and one of the shoes therein; Fig. 5 is a transverse section on the line 5—5 but with the locking dog in the inoperative position; Fig. 6 is a 30 similar section showing the dog in its operative position.

Referring to the drawing, 1 indicates a window frame, having a sill 2 and vertical side pieces 3. Resting upon said sill and having its ends secured between said side pieces is a slideway 4, the sides of which are formed with upwardly flaring inner surfaces. In said slideway can slide shoes 6, having downwardly converging sides. Each 40 shoe is formed near its outer end with an aperture in which is pivoted or stepped a pivot pin 7, depending from, and rigidly secured to, or formed integral with, a metal plate 8, secured upon the horizontal side of a longitudinal angular recess 5 formed in the bottom of each sash 9 at its inner side, said sashes being hinged together, as shown 45 at 11, at their inner or adjacent vertical

edges. By sliding said shoes away from one another in the slideway, the sashes 50 can be moved into the one plane and the window closed while by sliding the shoes in the opposite direction, or toward one another, the sashes can be placed at an angle with one another and the window opened. 55 A suitable locking device 13 is provided to lock the sashes in their closed position. The general construction, however, of sashes so movable forms no part of our present invention. The outer wall of said slideway 60 is formed, preferably at regular intervals with slots or recesses 12, open at the top. Into these recesses are adapted to swing locking dogs 15, contained in recesses 14 in said shoes and pivoted on horizontal longitudinal pivot pins 17 secured in the shoes, across said recesses 14, each recess being 65 formed at the top with an extension 16 sufficiently large for the insertion of a finger to engage the rear portion of the locking dog to swing it from their inoperative to their operative position to cause it to engage a slot 12. The upper edge of said dog will, in its inoperative position, rest in the recess 14 substantially flush with the 70 upper edge of the slideway, so as to be out of the way of the window sash when moving to its closed position. Since the bottom of each sash at its outer side is not cut away, it entirely closes and conceals, when in its 75 closed position, the slots or recesses 12 in the outer wall of the slideway, so that the window is of usual appearance.

We claim:

In combination with a window frame having a window sill, window sashes hinged together at inner vertical edges, the lower edges of said window sashes being formed on their inner sides with longitudinal angular recesses, a slideway secured upon said sill, and received in said recesses of the sashes and adapted to be concealed by the outer portions of the sashes when in their closed position, the outer wall of said slideway having slots or recesses open at the 95 top, shoes slidable in the slideway to which

the sashes are pivoted by vertical pivots, and a locking dog pivoted to each shoe and contained wholly in a recess therein, and arranged to swing out of said recess to engage an open-ended slot in the side of the slideway.

In testimony whereof we have hereunto

set our hands in the presence of two subscribing witnesses.

CHARLES W. ANTILL.
WILLIAM L. SCHMOLLE.
